UNITED STATES PATENT OFFICE.

HOMER T. HOOD, OF DETROIT, MICHIGAN, ASSIGNOR TO ROBERTSHAW MANUFACTURING COMPANY, OF YOUNGWOOD, PENNSYLVANIA, A CORPORATION OF PENNSYLVANIA.

BURNER CONTROL.

Application filed December 21, 1921. Serial No. 523,865.

To all whom it may concern:

Be it known that I, HOMER T. Hood, a citizen of the United States, residing at Detroit, in the county of Wayne and State of Michigan, have invented a new and useful Improvement in Burner Controls, of which the following is a full, clear, and exact description, reference being had to the accompanying drawings, in which—

10 Figure 1 is a view, largely diagrammatic and partly in section, illustrating one embodiment of the present invention;

Figure 1^a is a detail sectional view, on an enlarged scale, illustrating the thermostatically controlled valve;

15 Figure 2 is a similar view illustrating a modification; and

Figure 3 is also a similar view illustrating a still further modified embodiment of my 20 invention.

The present invention relates broadly to burners and burner systems, and more particularly to a form of burner control for liquid fuel burners.

25 At the present time it is customary to supply both liquid fuel and a fluid such as air or steam, to a burner in such manner as to effect an efficient mixture at constant pressures and with constant quantities of both 30 the liquid and the fluid. It has been extremely difficult, however, to effectively regulate the size of the flame of the burner. The present invention has for one of its objects the provision of means by which such a 35 regulation can be easily secured.

Also, with systems as commonly used at the present time, it is customary to so mount the thermostat, in case one is provided, that it will directly control the flow of the liquid fuel. This is very objectionable, as the 40 liquid fuel at times must pass through very restricted openings, and therefore has a tendency to clog the same and prevent the free flow of the fuel. By the present invention these objections are obviated and the thermostatic control, where one is provided, is so mounted as to be initially effective upon the air, steam or other fluid.

45 Referring more particularly to Figure 1 of the drawings, there is illustrated one embodiment of my invention comprising a supply pipe 2 for the liquid fuel. This pipe may be provided with any desired form of manual control valve 3 which regulates the 50 flow of the liquid fuel, which is preferably

under pressure, to a combined trap and strainer 4. After being strained the liquid fuel passes into a constant level chamber 5 the inlet to which is controlled by a float operated valve 6. Connected with the constant level chamber 5 below the level of the fuel therein, is an outlet pipe 7 adapted to conduct the fuel to the central passage 8 of a liquid fuel burner of suitable construction. The inlet to the passage 8 may in turn be 65 controlled by a regulating valve 9, as is customary in this art. In actual operation, it is desirable to install the burner in such manner that the passage 8 lies in substantially the same horizontal plane with the 70 level of the fuel in the constant level chamber 5.

For supplying the air, steam or other fluid under pressure, there is provided a second supply pipe 10, preferably provided at a 75 convenient point with a manually operable regulating valve 11. From the valve 11 the fluid under pressure is conducted to a thermostatically operated valve 12. This valve may be operated by a thermostat 13 immersed in a bath 14 the temperature which it is desired to control, or mounted in any other desired manner so as to be subjected to variations in heat. The valve 12 controlled thereby is preferably of the well known type provided with a small bleed passage or bypass 12^a whereby a constant minimum amount of fluid will always be permitted to flow therethrough to maintain a pilot flame. From the valve 12 the fluid 80 under pressure is conducted to the annular passage 15 of the burner. Connected between the fluid pressure line and the constant level chamber 5 is an equalizing connection 16 whereby the pressure conditions 85 existing in the line 10 may be transmitted to an air chamber provided above the level of the fuel in the constant level chamber, thereby forming an equalizing chamber. This connection may be of such nature that a flow is permitted therethrough to establish equal pressures on both the fluid and the fuel or it may be of such nature as to restrict the flow and thereby maintain proportional pressures, as desired.

With a construction of this nature, it will be obvious that as the temperature in the furnace 17, or other heating device, is raised, the thermostat 13 will be operated to gradually close the valve 12. As this operation 105

takes place, the amount of fluid under pressure will be decreased, thereby proportionately decreasing the amount of fuel supplied by the burner. This is true for the 5 reason that the fuel supplied will bear a definite relation to the pressure existing in the chamber 5 and to the aspirating effect exerted on the passage 8. Such a system of control is very advantageous, as the valve 12 10 is so positioned that it controls a fluid which readily passes through restricted openings. The accurate control of the fluid under pressure is in turn transmitted to the fuel so that an efficient control for the burner is 15 provided.

In Figure 2 there is illustrated a slightly modified embodiment of the present invention, in which parts corresponding to parts already described are designated by the 20 same reference characters with a prime affixed thereto. With this form of my invention the thermostatic control is entirely eliminated and the flame conditions are regulated by manually manipulating the 25 valve 11'. It will be obvious that a burner control such as illustrated in this figure embodies substantially the same principle of operation as that heretofore described, as the regulation of the fluid under pressure effects the desired regulation of the liquid 30 fuel.

In Figure 3 of the drawings there is illustrated a further modification of the present invention, in which parts corresponding to 35 parts already described are designated by the same reference characters with an *a* affixed thereto. With this form of the invention the constant level chamber 5^a is provided with an opening 18 to the atmosphere 40 whereby substantially atmospheric pressure is maintained therein, and the equalizing connection is eliminated. With an arrangement of this type, the regulation may be effected either automatically by a thermostat 13^a in the manner described in connection 45 with Figure 1, or manually with a valve 11^a, as described more particularly in connection with Figure 2. Where the equaliz-

ing passage is eliminated, the aspirating effect of the fluid under pressure is relied upon 50 entirely for effecting the withdrawal of the desired amount of liquid fuel.

With all of the forms of the invention illustrated, the controlling or regulating valves which are relied upon for producing 55 the initial regulation or control are positioned so as to be directly effective on a fluid which is easily controlled. In this manner, clogging up of the system is prevented and an efficient burner control is provided. 60

I claim:

1. In a burner control, a burner, a supply pipe for liquid fuel, an equalizing chamber in said supply pipe, a pressure pipe for supplying fluid under pressure to the burner, 65 an equalizing connection between said means and said equalizing chamber, and a thermostatically operated valve controlling the flow through said pressure pipe, substantially as described.

2. In a burner control, a burner, a supply pipe for liquid fuel, an equalizing chamber in said supply pipe, a float valve therein controlling the level of fuel in the chamber, means for supplying fluid under pressure to 75 the burner, an equalizing connection between said means and said equalizing chamber, and means for controlling the supply of fluid under pressure, substantially as described. 80

3. In a burner control, a burner, a supply pipe for liquid fuel, a chamber communicating with said supply pipe and adapted to receive fuel therefrom, a float valve in said chamber adapted to maintain a fuel level 85 therein substantially coincident with the center line of the burner, means for delivering fuel from said chamber to said burner, means for supplying fluid under pressure to said burner to draw the liquid fuel therefrom, and thermostatically operated means 90 for controlling the supply of fluid under pressure, substantially as described.

In testimony whereof I have hereunto set my hand.

HOMER T. HOOD.
